[57] CLAIM

The ornamental design for a fingernail decal, as shown
and described.

DESCRIPTION

FIG. 1 is a top plan view of a fingernail decal showing
my new design, the portion of a finger being shown in
broken lines for illustrative purposes only;

FIG. 2 is a top plan view thereof;

FIG. 3 is a side perspective view thereof;

FIG. 4 is a right side elevational thereof.

The rear of the fingernail decal is unornamented and the
decal is of conventional thickness.
